UNITED STATES PATENT OFFICE.

JAMES H. RAND, OF NORTH TONAWANDA, NEW YORK, ASSIGNOR, BY MESNE ASSIGNMENTS, TO REMINGTON RAND INC., OF TONAWANDA, NEW YORK, A CORPORATION OF DELAWARE.

TYPEWRITER ATTACHMENT.

Application filed July 31, 1924. Serial No. 729,209.

This invention relates to a typewriter attachment particularly adapted for use in preparing stencil sheets such as disclosed for example in my copending application Serial 5 No. 552,792, filed April 14, 1922, but attachments embodying the present invention are also applicable for use in typing cards or other sheets of paper.

In order more clearly to illustrate the 10 nature of the invention, I have shown one concrete embodiment in the accompanying drawings, in which—

Fig. 1 is a front elevation of the attachment, portions of the typewriter being shown 15 to illustrate its relationship with the typewriter;

Fig. 2 is an end view of the device;

Fig. 3 is a section on the line 3—3 of Fig. 1;

Fig. 4 is a plan view showing the attachment modified for mounting on a different form of typewriter;

Fig. 5 is a section on the line 5—5 of Fig. 4;

Fig. 6 is a fragmentary view of still another mounting for the attachment; and

Fig. 7 is a section on the line 7—7 of Fig. 6.

The particular embodiment of the invention chosen for the purpose of illustration comprises a frame preferably of aluminum made up of a back 1 and end members 2, integral with the back and extending at substantially right angles therefrom. The 35 end members 2 are connected together at the top by a strip 3, the ends of which are bent over the outside of the end members 2 and secured thereto by rivets. The bottom of the end members 2 are connected together 40 by a rod 4 which is held in place by screws.

In order to fit around a platen P of the typewriter the lower ends of the end members 2 are cut out at 5, slightly rearwardly of the rod 4. Formed in each of the end members 45 2 are slots 6 (Figs. 1, 2 and 3) to receive the bar B provided on the carriage of a well-known make of typewriters, and spring pressed hooks 7 pivoted by means of rivets 8 hook over the bar B to hold the attachment 50 in place. As mounted the back 2 rests against the guide plate G usually provided on these machines for guiding the paper fed to the platen.

Extending along the forward edges of the

end members 2 and secured thereto by rivets 55 are guides 9 which have flanges 10 for the margins of the paper. It will be evident that the paper is guided to the platen P by the back 1, and from the platen by the rod 4 under which it passes to the guides 9, the 60 strip 3 cooperating with the guides to position the stencil sheet or other paper so that it is accurately positioned in planes substantially perpendicular to the axis of the platen. In this way the margin of the typewritten matter may be made exactly parallel to the 65 margins of the sheet and by using the ordinary carriage stops the margin of the type-written matter may be made exactly the same on each of a series of cards or other 70 sheets. This is particularly important in making stencils for card indexes which are intended to be mounted in rows since it is desirable that the margins of the columns of the indexes on the several cards of a row be 75 in accurate alignment.

As shown in Figs. 4 and 5 the attachment may be provided with other means for mounting on typewriters of another well-known make, and in this form the back 2 80 is formed with a longitudinally extending lip 11 which hooks over the paper guide plate R usually provided on these machines. In order to hold the attachment in position arms 12 and 13 are secured by rivets to the 85 end members 2 respectively, extending at substantially right angles therefrom, and the arm 13 is bent to fit over the usual slide S on the guide plate R. The outer ends of the arms 12 and 13 are bent rearwardly to 90 receive screws 14 which are adapted to bear against opposite ends of the plate R thereby securely holding the attachment in proper position.

In order to mount the attachment on still 95 another well-known make of typewriter, which is usually provided with a substantially vertical paper guide plate H, arms 15 (Figs. 6 and 7) are secured to the end members 2 respectively and are provided adjacent their outer ends with clips 16 which are adapted to fit over the edges of the plate H, screws 17 being provided to hold the clips to the arms and draw them into engagement with the plate.

An outstanding feature of the invention consists in that the paper is guided to and from the platen and that the unitary con-

struction contributes to accurate positioning of the sheets. This also facilitates and renders more easy the cutting of stencils because the objectionable feature of continually adjusting the position of the sheet upon the platen is obviated. Another important feature consists in that the guides for the paper extend substantially tangentially to and from the platen in the regions where the paper leaves and meets the platen respectively.

I claim:

1. A typewriter attachment comprising elongate flanged guides for the opposite edges of the paper, means interconnecting the guides in predetermined spaced relation, and spring held means for detachably connecting the attachment to a typewriter in operative relation to the platen.
2. A typewriter attachment comprising means for guiding the paper, and catch means for detachably connecting the attachment to a typewriter in operative relation to frame parts of the platen, said guiding means including straight elongate guides for the edges of the paper after the paper passes over the platen and a pair of guides in juxtaposed relation to the front face of the straight guides.
3. A typewriter attachment comprising a frame, a spring pressed hook adapted to detachably mount said frame on a typewriter adjacent the platen, said frame having means for guiding paper to the platen, opposed guides for the edges of the paper

where it leaves the platen, and means cooperating with said guides for positioning the paper transversely and longitudinally of the paper.

4. A typewriter attachment for guiding paper to and from the platen comprising a guide frame having a back and opposed parallel sides, hook means adapted to detachably connect said guide frame to the typewriter frame, guides on said sides in opposed relation arranged to guide the edges of the paper where it leaves the platen, a member connected to said sides adjacent the lower end of the frame under which the paper passes from the platen, and a member connected to said sides adjacent the top of the frame cooperating with said guides for positioning the paper.

5. A typewriter attachment for guiding paper to and from the platen, comprising a frame having a back and opposed parallel sides, guides on said sides in opposed relation arranged to guide the edges of the paper when it leaves the platen, a connecting member for said sides adjacent the lower end of the frame adapted to form a guide for the paper adjacent the front of the platen, and a connecting plate for the front of said sides adjacent the top of the frame adapted to hold said paper in position when it has left the platen.

Signed by me at Boston, Mass., this 28th day of July 1924.

JAMES H. RAND.
